UNITED STATES PATENT OFFICE

CLARENCE B. LITTLE, OF DAYTON, OHIO, ASSIGNOR TO THE BROWNEll COMPANY, OF DAYTON, OHIO, A CORPORATION OF OHIO

AUTOMATIC STOKER

Application filed August 25, 1928. Serial No. 302,637.

This invention in general relates to stokers of the automatic class. In particular it relates to that class of automatic stokers in which there is means for regulating the amount of coal fed and the draft. In this invention it is possible to regulate the amount of coal in relation to the draft so that there might be a small feed of coal with a relatively large draft or a large feed of coal with a relatively small draft. After the arrangement has been made so as to adjust the amount of the draft in relation to the coal, the stoker mechanism can be operated at any speed and the draft accordingly accommodated.

It is a purpose of this invention to provide an automatic stoker in which the amount of coal to be fed may be regulated within a definite range and the draft may be adjusted so as to produce the required combustion to maintain the boilers at certain steam pressures.

For the purpose of illustration there is shown in the accompanying drawings a preferred embodiment of this invention which is here shown by way of illustration only.

Figure 1 is a front elevation of the furnace with a stoker attached thereto.

Figure 2 is a front elevation of the furnace with the stoker mechanism removed and part of the furnace in section.

Figure 3 is a view showing the fuel feeding device in plan, with the furnace in horizontal section, the mechanism for regulating the damper being shown by dotted lines.

Figure 4 is a side elevation of the furnace with the stoker mechanism attached thereto, showing the lower part of the furnace in section.

Figure 5 is a sectional view on the line 5-5 of Figure 6 through the stoker mechanism showing the means by which the feed is operated and adjusted and the damper adjusted, the parts in this, and subsequent views, being much enlarged as compared with the illustrations of like parts in Figures 1 to 4, inclusive.

Figure 6 is a section through the housing motor worm and worm gear on the line 6-6 of Figure 5, with the stoker drive mechanism in side elevation.

Figure 7 is a detail view showing, in plan, the mechanism for adjusting the rapidity of feed, and the position of the damper.

Figure 8 is a detail view, somewhat enlarged, of certain parts shown in Figure 7, on the line 8-8, Figure 7, looking to the left.

Figure 9 shows the crank arm for adjusting the pawl cam and the damper.

Referring to the drawings in detail, 1 designates the furnace mechanism as a whole. In front of this furnace is located the automatic feed or stoker means which is provided with a coal chute or hopper 2. In the lower part of this chute or hopper is located one end of the feed worm.

For the purpose of operating the stoker mechanism there is provided a motor 3 which has the ordinary motor shaft 4. To this motor shaft is attached a worm shaft by any suitable means, through which the other mechanism is operated. The stoker operating mechanism is enclosed in a housing 5. The worm shaft which is attached to the motor shaft is indicated by 6 and meshes with a worm gear indicated by the numeral 7. The worm gear 7 is carried upon a shaft 8 which is suitably mounted in the housing as indicated in Figure 6.

On the inner end of the shaft 8 is a crank or a crank pin 9 through which one end of a crank link 10 is pivoted, while the other end of this link 10 is pivoted as indicated by 11 to two plate members 12. These plate members are pivoted to the outer end of the worm feed shaft 13.

Between these plate members 12 there is pivoted a pawl 15 at the point indicated by 14, which engages teeth 16 on a ratchet wheel 17. The ratchet wheel 17 is mounted upon a shaft 13 and has for its object the rotation of the shaft 13. This is done by means of the structure hereinbefore described, consisting of the worm, the worm gear, crank, crank link, plate members 12, pawl 15 and the ratchet wheel 17. As the worm gear 7 rotates, it causes the link to move back and forth and rock the plate members 12 which actuate the pawl 15 to engage the teeth of the ratchet wheel 17 to give it intermittent rotary movement.

For the purpose of holding the ratchet wheel 17 against backward movement, there is provided a holding pawl 18 which is held in engagement with the ratchet teeth 16 by means of a spring 19. There is also pivotally mounted at 21 upon the shaft 13 a cam member 20 which has on one part thereof a cam surface 22. This cam surface is adapted to engage a roller 22' mounted on the pawl 15. 5 By adjusting the cam member 20 the time or point at which the pawl 15 engages the ratchet teeth may be determined and thereby the length of the stroke of the pawl 15 as it engages the ratchet teeth may be made 15 longer or shorter. For the purpose of adjusting the cam there is pivoted thereto at 23 a link member 24. To the other end of this link member 24 at the point indicated by 25 another link 26 is pivoted and is guided 20 in the frame 27. On the other end of the link 26 there is pivoted a stud member 28 which is engaged by a slot 29 in the end of an arm 30. This arm 30 is rigidly attached 25 to a shaft 31 which is supported by the frame by means of a bracket member 31'.

Extending from one end of the rod or shaft 31 is a crank arm 32 which has on the outer end thereof a handle 33 in which there is a plunger 34 having on the end thereof 30 a projection adapted to fit in holes herein-after described. The plunger fits within the handle member and is provided with a spring by means of which the plunger is kept in engagement with the holes until operated to 35 remove it therefrom.

Conveniently located at the handle end of the crank arm 32 there is an arcuate plate 37 which has a series of holes 38 adapted to receive the end of the plunger to hold it in 40 fixed position and to hold the mechanism herein-after described in adjusted relation. This handle is used to operate the mechanism that controls the position of the cam and 45 after the handle is moved to any desired point indicated by the holes 38, the plunger is placed within one of these holes, thereby holding the cam in a fixed position until the plunger is released. The damper means is also controlled by this same handle.

50 For that purpose there is attached to the rod or shaft 31 an arm 39 which has pivoted to the outer end thereof at the end 40 a link 41. This link is round in shape, especially so at the outer end and adapted to slide in the hole 42 provided in a stud 43. This link 41 is held in position with the stud 43 by means of a screw member 44.

The stud 43 is attached to one end of an 55 arm 45 in such a way that the stud may rotate with relation to the arm. The other end of the arm 45 is rigidly mounted or attached to a damper member 46 and horizontally mounted at a point indicated by 47 in the draft flue 48. It can be seen by the structure here described, that the length of the stroke

of the pawl 15 can be controlled by the movement of the arm 32 which regulates the cam that engages the roller on the end of the pawl.

It will also be noticed that by this same movement of the lever 32 the damper is opened or closed, or regulated to admit any desired draft. 70

Suitably attached to or connected in some way to the shaft 13 is a feed worm 49 which 75 is located in the lower part of the chute or hopper mechanism 2.

For the purpose of housing the worm and providing means whereby the fuel may be conducted by the worm, there is provided a 80 housing 50 which leads from the lower part of the chute to the lower part of the furnace, as shown in Figure 4. The furnace is indicated by 51, to the lower part of which the feed worm delivers the coal. The rear part 85 of the furnace is flared upwardly as indicated at 52. As the coal is fed from the chute or hopper through the housing 50 into the furnace, it is caused to pile up and roll over onto the grates, where combustion takes place 90 very rapidly. In fact, combustion takes place on all of the outer surface of the coal.

The fire box of the furnace 53 is provided with grates 54 which are of any convenient form and arrangement. The furnace is also 95 provided with ordinary doors 55. By means of this apparatus the feeding of the coal from the hopper or chute into the furnace may be so regulated as to provide a small or very large amount of coal to the furnace and at 100 the same time the amount of air admitted through the flue leading into the furnace may be controlled, so that combustion may either take place slowly or rapidly.

By this means intense heat may be produced or just such heat as is necessary to maintain the boiler in a low state of steam pressure. 105

By adjusting the member 41 in relation to the stud 43 the control of the damper may be 110 regulated without disturbing the control of the coal feeding mechanism. By adjusting the lever 32 both the coal feeding and the damper mechanism are controlled and operated by the same operation.

On the end of the worm shaft 6, remote from the motor and indicated by the numeral 48' is a conventional form of blower operated at a uniform rate of speed to deliver air to 115 the furnace.

Having thus fully described my invention, what I claim as new and desire to protect by Letters Patent is:

1. In a stoker, in combination with a furnace, means for feeding coal to the furnace at regular intervals including a motor having a worm shaft, a worm gear operated by the worm shaft, an eccentric operated by the worm gear, a pawl operated by the eccentric, a ratchet wheel operated by the pawl, a worm 125

- conveyor operated by the ratchet wheel, and a cam associated with the ratchet wheel and pawl to control the length of the feed stroke, means supplying air to the furnace, means to control the delivery of air to the furnace including the aforesaid motor, an air passage to the furnace, a damper in said air passage, an adjustable rock shaft, an adjustable arm and link connection between the shaft and the damper, and an arm and link connection between the shaft and said cam whereby the amount of air delivered to the furnace may be regulated to correspond to the amount of coal fed to the furnace.
2. In a stoker, in combination with a furnace, means for feeding coal to the furnace at regular intervals including a worm conveyer, a ratchet wheel, and pawl and operating means therefor for actuating the conveyor, a cam associated with the ratchet wheel and pawl to control the length of the feed stroke, means for supplying air to the furnace, an air passage to the furnace, a damper in said air passage, and means for simultaneously actuating said cam and damper including an adjustable rock shaft, an arm and link connection between said shaft and cam, an arm connected with said shaft, a link connected with said arm, and a slidable adjustable connection between said link and damper comprising an arm on the damper having a rotatable stud having an opening therein to receive said link, and clamping means for securing the link in various positions of adjustment in said stud.

In testimony whereof, I affix my signature.
CLARENCE B. LITTLE.
